FIG. 1.

FIG. 2.

FIG. 3.

FIG. 4.

UNITED STATES PATENT OFFICE.

FERDINAND HAUFF, OF QUINCY, ILLINOIS.

SIGN.

No. 926,326.

Specification of Letters Patent.

Patented June 29, 1909.

Application filed August 31, 1907. Serial No. 390,874.

To all whom it may concern:

Be it known that I, FERDINAND HAUFF, a citizen of the United States, residing at Quincy, in the county of Adams and State of

5 Illinois, have invented certain new and useful Improvements in Signs, of which the following is a specification.

My invention consists in making a sign of such curvature as to facilitate the reading of 10 letters placed thereon.

In the drawing Figure 1 is a front elevation of a sign embodying my invention. Fig. 2 is a top plan view of the same. Fig. 3 is a sectional view on the line 3—3 Fig. 1. Fig. 4 15 is a sectional view on the line 4—4 Fig. 1.

The sign is constructed substantially on the lines of a parabola curve in vertical cross section immediately in the center, a narrow central longitudinal portion thereof being 20 flat as at 6 while the ends of the portion 6, as well as the ends of the other portion of the sign are curved toward the front sharply as at 7 to give a converging effect. The top and bottom portions of the sign 8 and 9 being for 25 their major longitudinal portion flat, but at the ends drawn toward the front with a blunt curve as at 7, the said curve beginning at 9 and gradually merging from a flat surface to a curved surface at each end of the sign as at 30 10. The edge of the sign being concaved as at 11.

We will assume that the sign is 34 inches high by 50 inches wide, from outside of shell; a 50 inch tangent line touching the edges 35 across its width, at its center, will show a 12 inch depth to center of its concavity, that is; 12 inches from such tangent line to center body of sign; while a vertical tangent line,

from middle of top line of shell to its bottom line, the center of such vertical line being 5 40 inches from body of center of shell shows the incurve of top and bottom lines of shell.

11' is a wooden piece secured to the back of the sign and affords means for suspending said sign; 12 is a wire, or gas conduit, leading 45 into the center of the sign; 13 is an electric light bulb and 14 is a clamp ring secured to the light socket, said ring carrying arms 15 to which is attached a shield 16 placed immediately in front of the light to prevent the rays 50 of light shining in the face of a person looking at the sign.

The construction of the sign on a substantially parabola curve the flat portions 8 and 9 and the general perimeter of the sign result 55 in confining the light to the sign and bringing all letters on the sign directly in front of the eyes of a person reading it without perceptibly moving the eyes to bring all matter in focus instantly. 60

Claim—

As a new article of manufacture, a sign having a central longitudinal flat portion, comparatively narrow, with its ends curved toward the front to give a converging effect, 65 a top and bottom portion flat in their vertical axis, inclined toward the front and bent at their ends toward the front with a blunt curve, the front edge of the top and bottom members being concaved. 70

In testimony whereof I affix my signature in presence of two witnesses.

FERDINAND HAUFF.

Witnesses:

JOHN FUELHIER,
M. E. RASCHE.
